[57] CLAIM

The ornamental design for a case for a hairsetter travel kit, substantially as shown and described.

DESCRIPTION

FIG. 1 is a perspective view of a case for a hairsetter travel kit showing my new design;

FIG. 2 is a top plan view thereof;

FIG. 3 is an end elevational view thereof;

FIG. 4 is a front elevational view, the rear elevational view being identical; and

FIG. 5 is a bottom plan view thereof.
